DESIGN FOR A JACKET

Louis Cohen, New York, N. Y.

Application March 10, 1939, Serial No. 83,497

Term of patent 3½ years

To all whom it may concern:

Be it known that I, Louis Cohen, a citizen of the United States of America, residing in New York city, in the Borough of Manhattan, county and State of New York, have invented a new, original, and ornamental Design for a Jacket, of which the following is a specification, reference being had to the accompanying drawing, forming part thereof, wherein:

Figure 1 is a front view of a jacket showing my new design.

Figure 2 is a rear view of the jacket shown in Figure 1.

Figure 3 is an enlarged fragmentary view of the puffings covering the jacket shown in Figures 1 and 2.

The characteristic feature of my design resides in the combination on the jacket disclosed of the specific puffings covering the body and sleeve portion thereof.

I claim:

The ornamental design for a jacket, substantially as shown and described.

LOUIS COHEN.
